GRAVE LINING AND COVERING DEVICE

Original Filed Nov. 15, 1926

Patented Nov. 27, 1928.

1,693,062

UNITED STATES PATENT OFFICE.

GUSTAF A. STARK, OF ATWATER, MINNESOTA.

GRAVE LINING AND COVERING DEVICE.

Application filed November 15, 1926, Serial No. 148,349   Renewed September 23, 1928.

This invention relates to grave lining and covering devices.

It is the object of this invention to provide in connection with a casket lowering device,

5 novel means for concealing the lowering device and for lining a grave as a casket is lowered therein by the lowering device.

It is a further object to operate said means by the webbing straps of a lowering device.

10 These and other objects and advantages of the invention will more fully appear from the following description made in connection with the accompanying drawings, wherein like reference characters refer to the same or 15 similar parts throughout the various views, and in which:

Fig. 1 is a plan view of one embodiment of the present invention applied to a casket lowering device, certain of the parts being broken 20 away;

Fig. 2 is a vertical section taken on the line 2—2 of Fig. 1, as indicated by the arrow;

Fig. 3 is a vertical section taken on the line 3—3 of Fig. 1, as indicated by the arrow, 25 certain of the movable parts of the device being shown in full lines in one position and in dotted lines in another position;

Fig. 4 is a vertical section taken on the line 4—4 of Fig. 1, as indicated by the arrow; and

30 Fig. 5 is a perspective view of one portion of the embodiment of the invention illustrated in Fig. 1.

Referring to the drawings, a casket lowering device of standard construction is illustrated, including corner posts 7, side shafts 8, end shafts 9, and webbing straps 10, extending between the two side shafts 8, the ends of the webbing straps being releasably secured to the shafts 8 by staples 11, and wound upon 40 the shafts. A foot control pedal 12 is used for controlling the lowering of the device and a crank 13 for winding up the webbing straps 10 upon shafts 8 before or after using the device. Shafts 8 are preferably composed from 45 tubing and have removable central sections 14 slidably securable in the main sections of the shafts by pin and socket joints, small keys being formed at each joint to permit the sections 14 and the main sections of the shafts 8 to rotate as a whole. The lowering device is 50 of substantially rectangular shape and is adapted to be set up and situated over an open grave, whereupon a casket, such as the casket 15, indicated in dotted lines in Fig. 2, may be 55 placed on the webbing straps 10 and the foot control pedal 12 pressed downwardly to per-

mit the weight of the casket to carry the same downwardly into the grave, the webbing straps 10 assuming a substantially U-shape as the casket is lowered into the grave and as 60 the shafts 8 rotate towards each other.

In accordance with the present invention a rectangular frame 16 is provided of substantially the same type described in my co-pending

U. S. application for patent, filed November 15, 1926, Ser. No. 148,348, and entitled

"Grave covering and lining device". The said frame is made up of a plurality of pipe sections, securable together, certain portions of the frame being slidably together, as at 17,

70 and connectable by pin and socket joints, said frame having removable central sections 18 in the sides thereof for reduction of the length of the frame. A pair of wings are

secured one to each of the shafts 8 adjacent 75 to the ends thereof, and are adapted to extend inwardly from the shafts to lie in idle position in substantially a horizontal plane.

Each wing comprises end sections 19 loosely 80 securable at their inner ends to shafts 8 by straps 20 screwed or otherwise secured to end

members 19, the ends of the straps 20 being secured together by buckles 21. Outer side

members 22 are hinged to end sections 19 by 85 hinges 23, the said outer side sections 22 being adapted to extend at right angles to sections 19 when outwardly swung, the central ends of sections 22 being preferably beveled.

Intermediate sections 24 preferably having 90 their ends beveled are secured to side sections 22 by clips 25. End sections 19 are provided adjacent their outer ends with apertures adapted to receive therein the dowelled

ends of outer side sections 26, also being beveled at their central ends and being adapted 95 to be secured to central sections 24 by clips 25.

Sections 26 are incut at 27 to form notches 100 within which straps 10 are adapted to fit, the said notches being of slightly greater depth than the breadth of webbing straps 10 and of considerably greater length than the width of straps 10. Pivotaly mounted over notches

27 are keepers 28, the said keepers being pivoted at one end to sections 26 adjacent one end 105 of the notches 27, and having hook portions formed at their other ends adapted to engage with headed pins, illustrated as screws 28a secured to sections 26 adjacent the opposite ends of said notches.

Side shrouds 29 composed from sheets of 110 flexible material having hooks 30 secured in rings on the outer edges thereof are secured

to the sides of frame 16 by the hooks, the shrouds extending inwardly from the sides of the frame over shafts 8, resting upon the respective wings and depending downwardly 5 from the inner sides of the wings into the grave. Slits 31 are formed in the shrouds 29 slightly inwardly from the sections 26, straps 10 extending from shafts 8 through the slits 31 and over the portions of the shrouds extending over the outer portions of the wings. End shrouds 32 also composed from sheets of flexible material are secured by hooks 30, secured in rings on the outer edges of the shrouds, to the ends of frame 16 and to portions 15 of the sides of the frame, the shrouds 32 extending over the corner posts 7 and the end shafts 9 and depending downwardly therefrom into the grave to line the ends of the grave. Clips 33, having upper central 20 open portions, are placed about the central portions of the webbing straps 10 to be carried thereby, the clips having short chains or cables 34 secured to their lower sides and depending downwardly therefrom, the lower 25 ends of the chains 34 having secured thereto the plates 35 of preferably circular shape, and of a diameter slightly greater than the spacing between the inner sides of the two wings when the wings are held in horizontal position.

Preferably the various parts of the device will be taken all apart for transportation or storage when not in use. To assemble the device the various parts of frame 16 are secured 30 together, whereupon the frame 16 is placed on the ground immediately surrounding a casket lowering device placed over an open grave. The wings are then assembled by swinging the sections 22 outwardly from sections 19 on hinges 23, securing the dowelled ends of sections 26 in the apertures in sections 19 and sliding sections 24 in place between the various sections 22 and 26. Straps 20 are now loosely buckled about shafts 8 so 35 as to permit rotation of the shafts in respect to the wings. The wings, of course, will be placed below webbing straps 10 after they are secured to the shafts 8. Keepers 28 are now unlatched from pins 28^a, whereupon straps 40 10 may be inserted in the notches 27 and keepers 28 will then be swing to engage the hook portions thereof with the pins 28^a, keepers 28 extending over and across straps 10. Straps 10 will have already been prop- 45 erly extended through the slits 31 in shrouds 29. Shrouds 29 may now be hooked on to the sides of frame 16, the inner ends of the shrouds extending downwardly between the inner sides of the two wings into the grave. 50 Shrouds 32 are then secured by hooks 30 to the ends and sides of frame 16 and are extended downwardly over the corner posts 7 and shafts 9 into the grave. Clips 33 are now secured to the central portions of the webbing 55 straps, whereupon plates 35 may be engaged

underneath the inner sides of the opposing wings to assist in holding the wings in substantially horizontal position. The device is now ready for a burial ceremony, the shrouds completely covering the grave and the casket 70 lowering device with the exception of the central portions of webbing straps 10.

A casket 15 may now be deposited upon the webbing straps 10, whereupon the foot control pedal 12 of the lowering device may 75 be pressed, permitting the weight of the casket to carry the same downwardly into the grave. As the casket moves downwardly into the grave, webbing straps 10 will assume substantially a U-shape. Inasmuch as the 80 keepers 28 extend over straps 10 adjacent the shafts 8, the portions of straps 8 originally extending between keepers 28 and sections 26 will be quickly moved from horizontal to vertical position as the casket is first lowered, thereby swinging the wings downwardly into the grave and increasing the relative spacing between the two wings and allowing the plates 35 to be released from the inner sides of the wings. The wings will continue to be 85 swung downwardly into the grave until they approach the sides thereof, the wings carrying with them the shrouds 29, thereby causing the shrouds to line the sides of the grave as the casket is lowered. As the straps 10 are 90 payed out from shafts 8 as the casket is further lowered, the straps will slide in the notches 27, the portions of the straps in the notches being always vertically extended. Accordingly the wings and shrouds 29 will remain adjacent the sides of the grave, the shrouds 29 lining the sides. Shrouds 32 depending downwardly into the grave from the ends of the lowering device will line the end 95 walls of the grave. Accordingly the grave will be completely lined as a casket is lowered therein, thereby presenting an attractive appearance and covering up the sight of the bare earth forming the walls of the grave.

Although the wings are illustrated, as being secured to shafts 8 by means of straps 20, any other desirable means may be used for loosely pivoting the members 19 of the wings to the shafts. When it is desired to use the device of the invention in connection with a casket lowering device of shorter length than that illustrated, sections 24 may be removed and the respective portions 22 and 26 of the respective wings joined together, thereby shortening the length of the wings. It will, of course, be understood that the various sections of the wings may be joined together in manners other than those illustrated. If desired, shrouds formed from flexible sheets formed to imitate natural grass may be used, thereby creating a pleasing effect to the eye. The device of the invention can be used with various types of casket lowering devices.

It will, of course, be understood that va- 130

rious changes may be made in the form, details, proportions and arrangement of parts without departing from the scope of the invention, which, generally stated, consists in 5 the manner shown and described and set forth in the appended claims.

What I claim is:

1. The combination with a casket lowering device, having side shafts rotatable toward each other and webbing straps extending between said shafts, the ends of said straps being wound on said shafts, of means operated by said straps to line the walls of a grave as a casket is lowered into a grave by said device. 10
15. 2. The combination with a casket lowering device, having side shafts rotatable towards each other, and webbing straps extending between said shafts, the ends of said straps being wound on said shafts, of shrouds extending downwardly over said shafts into a grave, and means operated by said straps for causing said shrouds to line the walls of a grave as a casket is lowered therein by said device. 20
25. 3. The combination with a casket lowering device, adapted to extend over an open grave, said device having rotatable side shafts and webbing straps extending between and wound on said shafts, of wings having portions thereof overlying said straps and shrouds fitting over said wings and depending downwardly therefrom into a grave, whereby as a casket is lowered downwardly into the grave by said device, said wings will be swung downwardly by said straps thereby causing said shrouds to line the sides of the grave. 30
4. The combination with a casket lowering device adapted to be placed over an open grave, said device including rotatable side shafts and webbing straps extending between said shafts and having their ends wound thereon, of wings having slots therein through which said straps extend, and shrouds supported upon said wings, whereby as a casket is lowered into a grave by said device, said straps will carry said wings downwardly into the grave to cause said shrouds to line the sides thereof. 45
50. 5. The combination with a casket lowering device adapted to be placed over an open grave, said device including rotatable side shafts and webbing straps extending between said shafts and having their ends wound thereon, of wings having notches therein within which said straps are adapted to lie, keepers adapted to be secured over said straps to retain the same in said notches, and shrouds carried by said wings and adapted to be depended downwardly therefrom into a grave, whereby as a casket is lowered into a grave by said device, said straps will carry said wings downwardly into the grave to permit said shrouds to line the sides thereof. 55
60. 6. The combination with a casket lowering

device adapted to be placed over an open grave, said device including rotatable side shafts and webbing straps extending between said shafts and having their ends wound thereon, of wings extending inwardly from 70 said shafts and pivoted thereon for swinging movement downwardly into the grave, keepers mounted on said wings and adapted to be placed over said straps, shrouds supported on said wings and having depending portions 75 adapted to extend downwardly into the grave, whereby as a casket is lowered into the grave by said device said straps will carry said wings downwardly into the grave to permit said shrouds to line the sides thereof. 80

7. The structure defined in claim 6, and end shrouds extending over the ends of said lowering device and depending downwardly into the grave to line the ends thereof. 85

8. The combination with a casket lowering device adapted to be placed over an open grave, said device including rotatable side shafts and webbing straps extending between said shafts and having their ends wound thereon, of a frame surrounding said lowering device, wings pivotally mounted on said shafts, said wings having portions thereof overlying said webbing straps, side shrouds secured to the sides of said frame, extending over said side shafts, supported upon said wings and adapted to depend downwardly into an open grave, and end shrouds secured to the ends of said frame extending over the ends of said lowering device and adapted to depend downwardly into an open grave to 100 line the ends thereof, said side shrouds being adapted to be carried downwardly on said wings by said straps as a casket is lowered into a grave to line the sides of the grave. 95

9. The combination with a casket lowering device adapted to be placed over an open grave, said device including rotatable side shafts and webbing straps extending between said shafts and having their ends wound thereon, of wings adapted to be respectively 105 secured at their outer edges to said rotatable shafts and extensible inwardly towards each other, shrouds carried by said wings and means securable to said webbing straps and extensible under the inner sides of said wings 110 to retain the same in substantially horizontal position, said means being detachable from said wings as a casket is lowered by said device to permit said wings to swing downwardly adjacent to the sides of a grave, and 115 allow said shrouds to line the sides thereof. 120

10. The combination with a casket lowering device having rotatable side shafts and webbing straps extending between said shafts, the ends of said straps being wound on said shafts, of wings respectively mounted at their outer sides on said shafts for swinging movement from an idle substantially horizontal position downwardly into a grave, said wings being adapted to extend towards each other 125 130

in idle position, and plates depending from said straps, said plates being adapted to be interposed between and beneath the lower sides of opposing wings to hold the wings in substantially horizontal position when the lowering device is raised, but to slip away from said wings as a casket is lowered by said device.

11. The combination with a casket lowering

device having side shafts rotatable toward each other and webbing straps extending between said shafts, the ends of said straps being wound on said shafts, of flexible shrouds adapted to be operated by said straps to line the walls of a grave as a casket is lowered therein by said lowering device.

In testimony whereof I affix my signature.

GUSTAF A. STARK.
